GAS MAKING PROCESS

Alfred Johnson, West Brighton, N. Y., assignor
to Combustion Utilities Corporation, New
York, N. Y., a Corporation of Maine

Application June 19, 1929. Serial No. 372,112

19 Claims. (Cl. 48—202)

The present invention relates to processes and apparatus for the distillation and gasification of carbonaceous fuels, and more especially it concerns a process and apparatus for the concurrent 5 carbonization in place of high volatile bituminous fuels such as coal and the gasification of the residual coke in a semi-continuous succession of operations in an integral unit having a carbonization zone of limited annular cross section 10 positioned in the upper end of a gas generator casing directly above the fuel bed of the latter.

The advantages to be gained by the carbonization of fuels in thin layers is now well known. It has been determined that the rate of fuel carbonization by external heating—particularly 15 when employing temperatures within the low temperature carbonization range—is substantially inversely proportional to the square of the thickness of the fuel layer being carbonized;—for example a fuel layer 3" in thickness, when heated to a given temperature from each of the sides of the said layer, will carbonize in one-quarter the time required under similar conditions for carbonizing a 6" layer of fuel.

20 Carbonizing processes as at present commonly performed in vertical retorts or the like in which the coal is progressively fed downward through the retorts have not proven suitable for carbonizing thin layers of fuel, due to the mechanical difficulties, both in moving such thin 25 layers of material through the carbonizing chambers of such retorts and in discharging the coked product. The material tends to form a plastic sticky mass at an intermediate stage of 30 the carbonization and to adhere to the walls of the coking chamber.

Accordingly, it has heretofore been standard 35 practice to carbonize a relatively thick column of fuel; and this is essentially true where the 40 distillation apparatus has been directly associated with an apparatus for the complete gasification of the carbonized fuel. It is preferable that the fuel be fully carbonized before being moved onto the generator fuel bed. Because 45 however of the very slow rates at which thick layers of solid fuel can be heat-treated to yield a properly carbonized product, it has been necessary in the past either to undertreat the fuel so 50 that it was not completely carbonized, or alternatively to seriously reduce the carbonizing capacity of the installation by prolonging the carbonizing time of the charge.

55 Among the principal objects of the present invention are to provide in an improved manner for the rapid uniform carbonization of a column

of fuel; to provide for the uniform carbonization of such a column of fuel by indirect application of heat from a heating fluid flowing lengthwise of the column; to provide in an improved manner for regulating the temperature along a 60 column of fuel arranged in a thin layer and heated indirectly while held in place; to provide for the carbonization of coal in thin annular layers on water gas and/or producer cycle. These and other important objects will be clearly indicated in the course of the following 65 description, and in the appended claims.

Broadly considered the present invention involves the carbonization of a solid fuel such as 70 bituminous coal or lignite in elongated retorts of annular cross section, a plurality of which are suspended in a vertically-disposed heat-insulated gas generator directly above the fuel bed of the latter. The gas generator may be either a water 75 gas generator or a producer gas generator. The carbonization of the fuel is effected within the annular space confined between the concentric inner and outer walls of each of the said annular retorts. Heat for the carbonization is transmitted to the said walls of each retort, in part 80 by radiation from the incandescent fuel bed and in part by means of the sensible and potential heat in the gaseous products passing in contact with the said walls of the annular retorts, as will 85 be more specifically described hereinafter.

The rate of carbonization of the fuel has been 90 greatly accelerated according to the present invention by exposing a relatively thin annular column of the fuel to carbonizing heat applied preferably simultaneously to two opposite sides thereof. In practice the thickness of the fuel column annulus is less than 5" and is preferably about 3".

As rapidly as the annular column of fuel is 95 carbonized, the resultant coke is discharged directly onto the fuel bed of the gas generator by suitable means. The coke is then gasified in the said generator on standard water gas cycle or producer gas cycle, or upon a slightly modified series of cycles, the preferred modifications of 100 which are hereinafter set forth.

To offset or neutralize the effect of the uneven 105 vertical distribution of heat along the respective walls of the annular vertically mounted retorts during the producer gas and water gas cycles by 110 heat transferred from the hot gases, the invention comprises a further stage of indirectly heating the annular column of fuel being carbonized by means of highly superheated steam passed in downrun contact with either the inner or the 110

outer walls of each retort, but preferably with both of them, the said superheated steam transferring portions of its heat during such passage to the upper relatively cooler end of each of the 5 retorts while itself being sufficiently cooled in its downward passage, so that as it moves past the lower portions of the respective retorts which are constantly exposed to the heat directly radiated and that otherwise conveyed from the in- 10 candescent fuel bed, the stream acts to absorb heat from the said lower portions so as to lower the temperature of the latter. In this manner the downrun steam functions both as a carbonizing agency and as a means for equalizing the 15 retort wall temperatures at the respective end portions thereof. This tends to preserve the life of the retorts. Preferably potential heat recovered from the waste blast gases from an earlier cycle is employed for superheating the steam em- 20 ployed in the last named or downrun steam cycle.

Undesirable variations in temperature between the lower and upper ends of the carbonizing retorts also can be prevented in large part by the 25 successive addition of secondary air around the outer walls of the retorts at suitable points spaced vertically of the retorts. The amounts of such air preferably are so controlled as to effect the combustion of predetermined proportions of the gases issuing from the fuel bed at 30 different elevations lengthwise of the generator housing. This further increases the temperature of the hot gases contacting with the retort walls and particularly those portions of the lat- 35 ter which are more remote from the generator fuel bed.

To further facilitate the uniform carbonization of the fuel where the said vertical temperature gradient exists, the outer of the concentric 40 walls of each retort may be slightly tapered outwardly in a downward direction so that the thickness of the coal layer in the lower portion of the annular carbonizing zone, which is subjected to relatively higher temperatures than the 45 fuel in the upper portion thereof, is thicker in annular cross section than the latter. The relative thickness of the fuel layer at the respective upper and lower portions of the fuel column is preferably adjusted in accordance with the above 50 mentioned relationship between the thickness of the fuel layer and the time required for its carbonization.

To further facilitate the rapid carbonization of the annular fuel column, the inner retort wall 55 is adapted to be filled with refractory materials such as checker brick, Raschig rings, or the like which act to absorb heat from the hot gases passing along in contact with the inner wall of the retort, and to transfer such heat to the layer 60 of fuel being carbonized. This refractory material is very efficient as a heat-absorbing and transfer means when employed in the manner indicated, as shown by the fact that the portion of 65 the carbonization effected by transfer of heat from the inside surface of the annular fuel layer when the refractory filling material is not employed, amounts to less than one-half of the portion of the carbonization effected by heat transferred through the inner wall of the annular retort when the inner retort member is packed with 70 this refractory material.

In carrying out the process, the available heat 75 in the hot gases employed in heating the respective inner and outer walls of the retorts is preferably balanced in accordance with the total area

of the wall surfaces exposed to the said heat, so as to facilitate the carbonization of the fuel uniformly from both of the said retort walls.

Referring now to the accompanying drawings which show a preferred form of the apparatus 80 exemplifying the present invention:—

Fig. 1 is a vertical cross sectional view of a preferred form of a carbonizing and gasification apparatus, parts thereof being broken away; 85

Fig. 2 is an elevational view on a somewhat larger scale, showing the upper end of the generator housing and certain of the parts associated therewith, portions thereof being cut away, and other portions being shown in section; 90

Fig. 3 is a horizontal section of the apparatus taken along the line 3—3 of Fig. 2 looking in the direction of the arrows; 95

Fig. 4 is a chart which indicates the relationship between the carbonizing capacity of the retort and the thickness of the layer of fuel being carbonized within the scope of the present invention, at various indicated temperatures within the preferred carbonization range; and 100

Fig. 5 is a chart that indicates the relationship existing between the carbonizing capacity of a 100 retort and the temperature at which the carbonization is carried out, for definite thicknesses of fuel layers. 105

In the drawings 10 designates a vertically arranged, gas-generating apparatus suitably lined 110 with refractory material throughout and provided with a cylindrical side wall 11, a base or bottom member 12, and a closed top 14. The side wall 11 is suitably constricted at an intermediate portion thereof to form a lower portion 15 of reduced cross section. A grate 17 of usual construction is positioned in the bottom of the generator 10 above the base 12, the generator also being provided with the usual stoke holes 19—19 in its side walls adjacent the grate. Any type of 115 grate, as for example, a non-clinkering grate, may be substituted for that shown.

For introducing air under pressure into the lower portion of the generator casing, a pipe 21 controlled by valve 23 extends through the side 120 of the generator below the grate 17 and is connected with a suitable source of air under pressure.

Supported from the top member 14 of the gas generator and disposed in circular arrangement 125 at uniformly-spaced intervals are a plurality of depending, elongated hollow tubular retort members 29 of steel or other suitable heat-resistant metal or metal alloy such as hybnickel. The depending tubular members 29 preferably taper 130 outwardly in a downward direction, and have their enlarged lower ends positioned near but somewhat above the constricted portion in the generator casing.

In a typical installation, there is approximately 135 a 1" difference in cross-sectional diameter of the said member for each 8 feet of the length thereof.

The upper end of each of the retort members 29 extends through the generator top 14 and to 140 a point substantially thereabove, and each is provided with a flanged cover plate 31 having a relatively large, centrally-disposed aperture 33 therein, and having a second aperture 35 located 145 therein near the peripheral margin of the cover plate 31.

A tubular metal curtain 37 is mounted on the under surface of each plate 31 concentric with and surrounding the aperture 33, and it extends 150 downward within the retort member 29 to a point

adjacent the lower surface of the generator top 14, so as to define an annular space between the retort wall and the said curtain. A pair of spaced, depending curtain members 39, 39 extends radially from the outer edge of the curtain 37 within each retort to the adjacent inner retort wall on respective sides of the aperture 35 to provide a passageway leading from the interior of the retort to the said aperture. Other radial members 10 40, 40 divide the remainder of the annular space between the curtain 37 and the retort 29 into a plurality of parts.

Each of the tubular retort members 29 has disposed therein and concentric therewith a generally cylindrical hollow inner retort member 41 having the ends extending beyond the ends of the member 29. Each of the inner retort members 41 is made of suitable resistant metal or alloy such as hybnickel, and is adapted for 20 limited vertical movement longitudinally of the concentric member 29.

The lower margin of each of the members 41 is flared or bevelled outwardly and extends laterally beyond the bottom margin of the concentric retort member 29,—the arrangement being such that upon moving the inner member 41 vertically upward the said flared lower end of the latter engages the bottom margin of the member 29 and forms a substantially gas-tight seal for the 30 bottom of the annular chamber defined between the pair of concentric retort members 29, 41. The construction of the concentric retorts 29, 41 is preferably such that the annular fuel receiving space defined therebetween is less than 5" in effective annular width, and the preferred optimum width of this annular space is approximately 3".

Each of the retort members 41 is substantially 40 constricted adjacent the upper end of the retort member 29 to form an upper-end valve portion 45 of greatly reduced cross section. The said portion 45 extends vertically upward through the aperture 33 in the cover plate 31, and its extreme upper end is closed by a cap 45 46. The upper portion of each member 41 is operatively secured to a housing member 47 of a cushioning or shock-absorbing device, a second member 49 of the said device being adjustably secured to the piston 51 of a hydraulic cylinder 50 53 which is utilized for raising and lowering the retort member 41. The said cylinder is mounted upon a suitable superstructure 55 supported upon the top of the generator by the column 56. Operatively interposed between the members 47, 55 49 of each cushioning device are a pair of concentrically disposed compression springs 57, 58, which are so arranged as to resist the tendency toward downward movement of the respective inner retort 41 under the influence of its own weight and that of the fuel being carbonized.

An elongated slot or opening 59 is provided in the upper constricted portion of each of the inner retorts 41 at a point above the top plate 31. A hollow T-shaped casting 61 surrounds the portion 65 of the member 41 having the said slot 59 therein, and provides an annular chamber adapted to be in free communication with the interior of the member 41 only when the latter is in its uppermost position. The interior of the member 41 is adapted to be in communication with the upper end of the annular fuel space when the former is in its lowermost position. A stuffing box associated with each top plate 31 furnishes a gas-tight seal between the interior of casting 61 and the 70 annular fuel space and comprises a housing 68

in which is mounted a metal collar or seal ring 69 provided with a plurality of grooves in its inner peripheral surface, each adapted to accommodate a contracting piston ring 71 for cooperation with the adjacent surface of the inner retort member 41. A set screw or the like 73 cooperates with the housing 68 to prevent movement of the collar 69 with respect to the inner retort member.

The upper end of the T-shaped casting 61 has an opening therein through which the constricted upper end portion 45 of the inner retort member is adapted to extend. A stuffing box 75 of usual construction is mounted upon the casting 61 around the portion 45 and seals the interior of the casting from the atmosphere. The said interior of casting 61 is connected by pipe 63 controlled by valve 64, to a collecting main or junction box 65 centrally located on the top 14 of the generator.

For charging fuel to be carbonized into the annular space between each pair of concentric tubular retort members 29, 41, a fuel charging hopper 91 is centrally mounted upon the superstructure 55. The hopper 91 is provided with a gas tight closure member 93 and is divided into three superposed compartments 95, 97, 99, by a pair of vertically-spaced funnel shaped partitions 101, 103, each open at the lower end. Leading from a conical mid-portion 105 of the bottom of the hopper 91 are a plurality of feed lines 107, 107, 105 adapted to convey fuel to each of the annular spaces between the inner and outer retort members 29, 41. Each of the fuel feed lines 107, 107 has a suitable gas tight valve 109, 109, therein, and the lower end of each line 107 is branched adjacent the generator top to form fuel feed pipes 111, 111, which open into the upper end of one of the annular retort spaces through openings in opposite sides of the cover plate 31 between the metal curtain 37 and the outer retort wall 29.

For conveying fuel from the storage compartment 95 into the compartment 97 at a uniform rate, a positive feed mechanism is provided comprising a screw conveyor 113 mounted upon the upper portion of member 101 and driven from a suitable source of power through pulley 115 and belt 117. The funnel shaped member 103 has a central opening located directly above the mid-portion of the bottom of the hopper 91.

The upper closure member 93 of the hopper 125 is controlled by a hydraulic cylinder 127 functioning in the manner shown, through a bell crank 129.

The upper portion of the generator casing 10 is connected by means of the passageway 131 with 130 the upper portion of a regenerator 133 of well known type provided with checkerwork 135 of a heat refractory material, the said passageway 131 being provided with a cut-off valve 132. The lower end of the said regenerator is connected 135 with a waste heat boiler or economizer 137 by means of a passageway 139 having therein a shut-off valve 145. The gas outlet end of the economizer communicates with a stack 141 provided with a hydraulically-operated draft regulator or 140 closure 143. The lower end of the regenerator is also directly connected with the stack 141 by means of pipe 147 having valve 149 therein, for by-passing the economizer 137 when desired.

The upper end of the regenerator 133 is connected by means of a pipe 151, controlled by a hydraulic valve 153 and a check valve 154, with a lean gas tuyer 155. One end of the latter is connected with the collecting main 65, the other end thereof leading to the usual set of lean gas 150

coolers and scrubbers and to a lean gas holder (not shown). A hydraulic valve 157 and a check valve 158 are provided in the pipe 155 between the point at which the pipe 151 opens into it and the said lean gas coolers.

For conducting lean gas from the base of the generator casing below the grate to suitable gas holders, a gas tuyer 159 controlled by valve 165 has one end thereof opening into pipe 21 at a point between the said casing and the valve 23. The other end of the tuyer 159 is connected with the pipe 155 at a point therein between the valve 157 and the lean gas coolers. A branch pipe 161 controlled by valve 163 connects the stack 141 with the pipe 159.

For introducing steam into the apparatus, a pipe 167 controlled by valve 173 has one end thereof connected to a suitable source of steam under pressure,—the other end of the pipe 167 opening into the lower end of the regenerator 133. A branch line 169 controlled by valve 175 connects the steam pipe 167 with that portion of pipe 21 between the generator 10 and the valve 23.

For distributing secondary air into the generator casing immediately above the fuel bed and at vertically-spaced points in the generator casing adjacent the annular retorts 29,—and also for conducting air for combustion to the upper end of the regenerator 133,—a branch conduit 177 controlled by valve 179 leads from the air pipe 21 into the upper end of the said regenerator. An intermediate point in the line 177 is connected by pipe 181 with a vertically-disposed manifold 183. The latter is connected respectively by valve-controlled pipes 185, 187, 189, with each of a plurality of vertically-spaced bustle-pipes 197, 199, 201, surrounding the generator casing. Each of the said bustle-pipes has leading therefrom a plurality of radially disposed valved pipes 203 provided with suitable air injecting nozzles 205 extending through the generator wall, the arrangement preferably being such that the lower set of nozzles extends through the constricted lower portion of the generator casing immediately above the fuel bed therein,—an intermediate set of nozzles extends into the casing 10 at approximately the same elevation as the lower ends of the retorts 29, and another set of nozzles extends through the casing at approximately the same elevation as the mid-portion of the retorts 29.

For removing the gases and vapors as they are formed in the annular carbonizing space between the respective pairs of retort members 29, 41, during the carbonization of the fuel therein, each cover plate 31 has mounted thereon a header or casting 207, connecting the said annular fuel space through a valved pipe 209 with a bustle-pipe 211. The latter is connected by pipe 213 with a set of primary rich-gas coolers and scrubbers and therethrough with a rich-gas holder (not shown). A pipe 215 extends into the header 207 for use in injecting water into the vapors flowing therethrough for condensing tar and the like present in such vapors. A steam pipe 217 extends into each of the fuel feed lines 107 immediately below the valve 199 therein; and a steam pipe 219 extends into the upper portion of the space confined between each of the tubular curtains 37 and each retort member 29. Steam is preferably introduced into the carbonization zone through the steam lines 217 and 219 for the purpose of preventing the distillation gases from rising into the feed lines 107 and into the curtain 37 where tar and the like might be condensed and deposited.

For carburetting the blue gas made in one of the cycles of the process according to one modification a pipe 221 leading to a source of liquid hydrocarbon or other fluid carburetting medium has an end thereof opening into the upper portion of the regenerator 133, the said pipe being preferably provided with a spraying or atomizing nozzle or the like 223.

While the invention is susceptible of wide modification, depending on whether it is desired to produce coal gas, blue gas, a mixture of coal gas and water gas, or a carburetted water gas,—the following example is given solely to illustrate a preferred application of the process in the production of a modified blue gas. Assuming that the generator is provided with an already ignited fuel bed of coke or the like as produced in accordance with the present invention, a charge of fuel to be carbonized filling the annular space between the inner and the outer retort members of each pair thereof, a blast of air is introduced through pipe 21 below the grate 17 and is passed through the burning fuel in the base of the generator, the said air being mixed if desired with a relatively small amount of steam for temperature control purposes. The air blast is preferably continued for approximately two minutes, the fuel in the fuel bed becoming incandescent, and producer gas being formed. The resultant products of primary blast normally issue from the upper surface of the fuel bed at about 1600° F. Secondary air is also admitted to the generator just above the fuel bed during this period of the blast for the purpose of burning a part of the gases as they leave the fuel bed to assist in raising the temperature of the said gases to approximately 1900° F., this being the preferred temperature for the gases employed in heating the refractory material positioned within the inner one of each pair of concentric retort members. The products of the primary air blast are then divided, part thereof moving upward within the refractory-filled inner members and being withdrawn through the respective slots 59 in the upper end thereof and being conducted away through the junction box 65 and lean gas pipe 155. Part of this said lean gas may be introduced into the upper end of the regenerator 133 through line 151 where it is burned in the presence of air introduced through the pipe 177 for the purpose of heating the checker work in the regenerator. The resultant products of combustion of this portion of the lean gas are conducted downwardly through the regenerator and from there they may be led through the waste heat boiler and through the stack to the atmosphere. The balance of the lean gas flowing in pipe 155 is conducted through valve 157 through a lean gas cooler to a lean gas holder or to a common mixing holder.

Another portion of the gases leaving the generator fuel bed pass upwardly around the outer retort member 29, giving up their heat through the said retort walls to the fuel being carbonized. These cooled gases after such heat exchange flow from the generator through passageway 131 into the upper part of the regenerator where they mix with the blast gases entering the latter from the lean gas line 155 and may be burned with the latter for the purpose of heating the checker work in the regenerator 133. As the hot blast gases pass upwardly in the gas generator, predetermined amounts of air are introduced into and mixed therewith at a plurality of points spaced vertically of the generator, for the pur-

pose of maintaining the various portions of the outer retort walls at the desired temperature and for uniformly carbonizing the fuel.

At this point in the process the air blast is discontinued, valves 23, 191, 193, 195, 143, and 179 being closed, and the uprun make cycle is begun. Steam is admitted into the lower part of the generator beneath the grate by opening valve 175 in the steam line 169, steam valve 173 being closed. The blue gas formed by the steam in passing upward through the incandescent fuel bed is again divided, as in the previous or air blast cycle, a predetermined part of the hot blue gas being conducted along each refractory-filled inner retort member to assist in supplying heat thereto for the carbonization of the annular layer of material. This part of the blue gas thereafter passes through the ports 59 in the upper end of the inner retort members and through the lean gas bustle-pipe and tuyer 155 to the primary lean gas coolers and thence to storage. It may be stored in a separate holder from the producer gas previously conducted through the pipe 155, or it may be mixed with the portion of the primary blast gases that were taken to storage during the first cycle of the operation. A second predetermined portion of the blue gas generated in the second or uprun make cycle passes upward through the generator in contact with the external retort walls and is thereafter conducted from the generator through the passage 131 and the pipe 151 to the tuyer 155 where it mixes with the blue gas passing upwardly through the inner retort member and is conducted therewith through the lean gas coolers to storage.

During this uprun make cycle the fuel bed is rapidly cooled and the proportion of the heat radiated to the retort members from the incandescent fuel bed falls off appreciably. In order to maintain a satisfactory uniform coking temperature vertically along the fuel column during this cycle, sufficient air preferably is introduced through the pipes 203 to burn predetermined portions of the said blue gas so as to maintain the hot gases contacting with the inner and outer walls of the annular fuel column at the desired temperature during such contact. After the uprun cycle has been in operation for the desired length of time, it is terminated by closing the steam valve 175, the various valves 191, 193, 195 in the air line, and valve 157.

A downrun cycle is now started during which steam is admitted through line 167 into the lower portion of the regenerator, the valves 145 and 149 respectively connecting the bottom of the regenerator with the waste heat boiler and with the stack being closed, and the valve 165 in conduit 159 being opened. The steam is drawn upwardly through the regenerator, at the same time being highly superheated by heat transferred thereto from the highly heated checker work. The thus superheated steam is thereafter divided if and as desired into two portions. One of the said portions passes through the passageway 131 into the upper part of the generator casing, and descends therein, in contact with the walls of the outer retort members 29. The superheated steam, being at a higher temperature than that of the upper portion of the said retorts gives up heat to the latter, and is itself cooled and again absorbs heat from the lower portions of the retorts adjacent the hot generator fuel bed in a manner to offset the heating of the lower portions of the respective retort members to

higher temperatures than the upper portions thereof by the heat radiated from the fuel bed and by the sensible and potential heat of the gases formed in the two previous cycles. The remaining portion of the superheated steam passing upwardly through the regenerator, is conducted through pipes 151 and 155, the junction box 65 and the slots 59, and into the inner one of each of the pairs of concentric retort members. The said superheated steam then flows downwardly through the said members, giving up its sensible heat to the refractory fillings thereof, and it thereafter passes through the hot fuel bed 220. The blue gas thus formed by reaction of this steam with the highly heated fuel is conducted through conduit 159 to the primary lean gas coolers and thence to storage.

The down run cycle preferably lasts for about one minute and a quarter, after which a short uprun of purge steam is effected preparatory to again starting the air blast of another cycle. The purge steam and gases carried thereby are preferably conducted either to lean gas holders or exhausted to the atmosphere.

The distillation products obtained during the carbonization of the fuel containing for example various liquefiable and gaseous hydrocarbons, coal gas, tar, water vapor, ammonia and the like, are withdrawn continuously from the upper part of the annular fuel space during each of the above mentioned cycles and pass through header 207, bustle pipe 211, and the pipe 213 to a set of primary rich gas coolers preferably under subatmospheric pressure, and thence to a rich gas holder or a common storage holder.

These gas-making cycles are continuously repeated in the order given until the carbonization of the fuel in at least one of the retorts has been completed. Thereupon the inner retort member 41 is moved downward by operating the hydraulic cylinder controlling it, and the carbonized material is discharged by gravity downwardly onto the generator fuel bed. The flared portion of the bottom margin of the inner retort member functions as a support for the fuel column when it is in its upmost position, and it also acts as a valve to prevent substantial proportions of the heating gases such as producer gas and the like from passing to the fuel column and escaping into the rich gas offtake during the carbonization period. When the inner retort member is in its lowered position, the flared bottom thereof assists in breaking up large lumps of coke falling upon it during the discharging process.

The retort pairs are preferably filled in succession in such manner that the carbonization of the contents of one retort at a time is completed, and so that the successive dumping of the carbonized fuel from the various retorts onto the generator fuel bed maintains the latter at a substantially constant level and insures a uniform distribution of carbonized fuel on the surface of the fuel bed. The discharging of the coke material onto the generator fuel bed is preferably done during the downrun cycle, and any fine dust and the like escaping into the generator is drawn into the fuel bed 220 and does not interfere with the process.

Lean producer gas and the like are prevented from flowing through the space lying between the two concentric retort members during the time that the inner member is lowered for discharge of coke, due to the fact that the slot 59 then is positioned below the seal ring 69. During this time valve 209 is closed to prevent the pas-

sage of lean gas into the rich gas bustle-pipe 211. When the inner retort member is again raised to its former position with its flared lower margin in sealing contact with the lower margin of the outer retort member, the slot 59 again permits communication between the inside of the inner retort 41 and the junction box 65, and concurrently breaks communication between the latter and the annular fuel space. The said 10 annular fuel space is thereupon again charged with fresh fuel from the fuel hopper by operation of the conveyor 113, the charging door 93 at the top of the hopper being closed and the proper feed valve 109 being open.

15 Preferably the compartment 95 holds just sufficient fuel to properly charge one of the said annular retort assemblies. The conveyor 113 permits a uniform, determinate rate of charging fuel to each of the said retort assemblies, regardless of the amount of fuel in the hopper. The fuel charging may be discontinued at any stage by stopping the conveyor 113. A limited downward flow of steam through the fuel charging pipes 107 into the retort offsets any tendency 20 for distillation gases to collect in these pipes. The current of steam introduced into the upper portion of each retort between the inner retort member 41 and the metal curtain 37 prevents the accumulation in the space of distillation gases 25 which might deposit therein objectionable materials such as tar.

According to a modification of the process in which a carburetted combustible gas is produced, the uprun make cycle is so controlled that the gas 30 passing upward through the generator is at least in large part conducted into the regenerator by properly setting or closing the valves 157 and 158, and opening the valves 153 and 154, the said gases then being conducted downward through the 35 highly heated checkerwork in the regenerator. Simultaneously a spray of suitable carburetted fluid such as a hydrocarbon oil or the like is introduced into the upper portion of the regenerator and if necessary is vaporized and fixed at 40 the temperatures existing therein. The enriched blue gas is conducted from the lower end of the regenerator direct to the pipe 141 and, through branch pipes 161 and 159, to suitable gas coolers and scrubbers and then to storage,—the stack 45 valve 143 being closed. The economizer is preferably bypassed to avoid the possibility of tar and the like condensing in the flues thereof.

In like manner the last portion of the hot producer gases formed in the generator during 50 the blast cycle may be carburetted by spraying a carburetted fluid into that portion thereof which is passed downward through the highly heated checkerwork in the regenerator. The introduction of air to the regenerator through the air pipe 177 is preferably discontinued prior to the introduction 55 of the carburetted fluid into the said gases.

Instead of conducting all of the gases formed in the generator 10 during the uprun make cycle 60 through the regenerator, which here acts as a carburetor, a portion or all of the gases passing through the inner retort members of each pair may be conducted direct to lean gas coolers and to storage with or without portions of the gases 65 leaving the generator through the passageway 131, by suitable adjustment of the check valves 154 and 158.

70 Although both the inner and the outer retort members of each concentric pair are preferably fabricated from the same kind of heat resistant

metal, it is within the scope of the present invention to make the inner retorts of different metal or alloy than that of which the outer retorts are made, so that they will exhibit different physical characteristics under the conditions of use. In order therefore to compensate for any unbalanced elongation of the inner retort members under the effect of their own weight at the high temperatures employed, and to properly maintain a substantially gastight seal between the lower ends of the inner and outer retorts, the extreme upper end of the inner retort may be threaded externally for cooperation with threads formed upon the interior of the lower end of the housing member 47. Other similar means for 80 accomplishing the same result may be employed if desired. For example, the flared bottom of the inner retort of each pair may be separable from the tubular portion of such inner retort and may be adapted for adjustment longitudinally thereof. 85

The compression springs 57 and 58 permit the raising and lowering of the inner retort member without undue jarring and injury to the apparatus.

90 It will be obvious that other methods of charging coal into the retort may be substituted for that specifically shown and described. It is also within the spirit of the present invention to make the outer retort member cylindrical while employing a reverse taper on the inner retort member so that the sides of the latter slope inwardly in a downward direction; or if preferred both inner and outer retort members may be slightly tapered.

95 By employing a cylindrical inner retort member, and providing the outer retort with an outward and downward taper, it is possible to vary the thickness of the annular fuel layer to compensate for the usual vertical temperature gradient along the retort walls, especially in instances where the 100 said gradient has not been substantially eliminated by the combustion of effective amounts of secondary air as already described. In this way it is possible to appreciably increase the carbonization capacity of retorts of the type here shown 105 and described at approximately no additional cost. The relative proportion of the carbonizing heat distributed along the respective surface of the inner retort and the outer retort wall may be controlled by suitable vacuum-producing means 110 arranged in the lean gas offtake line from either of the said retort members or by pressure control 115 flow involving the use of regulating valves hereinbefore mentioned.

120 An apparatus construction in which a group of four uniformly spaced carbonizing retorts is supported in the upper part of a gas generator housing has proven to be very efficient and gives a very high carbonizing capacity per unit of time per square foot of metal heating surface employed. 125 The process is preferably carried out with effective retort temperatures of from 1050° F. to 1500° F. At temperatures much in excess of 1500° F., while the rate of carbonization is accelerated, there is a 130 tendency toward cracking of the tar vapors, which interferes with the production of primary tar and reduces the tar residue credit, both from the point of yield and quality. On the other hand at temperatures substantially below 135 1050° F., the carbonizing capacity of the assembly is materially reduced, when using the above-mentioned preferred thickness of coal or a thicker layer thereof, until a point is reached at which the 140 number of retorts required in order to permit the 145 150

continuous operation of the generator introduces many structural difficulties.

It is within the purview of the present invention to utilize for carbonizing the fuel both the luminous and the non-luminous or obscure radiations from the incandescent generator fuel bed; and the area of that portion of the tubular retort surface which is exposed directly to such radiated heat is preferably the maximum which is consistent with the maintenance of a suitably thin fuel layer in the carbonizing zone.

Fig. 4 clearly illustrates the rapidly increasing rate at which fuel is carbonized when exposed to heat in the low temperature carbonization range, 15 in layers 5" in thickness or less. The particular values for temperatures of 1050° F. to 1400° F. and 1500° F. are shown. Ordinarily in carbonizing fuel in annular layers over a water gas generator, certain difficulties are encountered where 20 fuel layers of over 5" in thickness are employed, due to the excessive retort space required to carbonize the necessary amount of fuel to serve the generator fuel bed, and to the resultant excessive cost of the apparatus assembly.

Fig. 5 illustrates the effect upon the carbonization capacity of a retort assembly due to varying the carbonization temperatures employed. This effect is separately indicated for fuel layers respectively 3" and 5" in mean thickness, between 30 temperatures of 1050° and 1800° F. However, at temperatures below 1050° F. the carbonization capacity of the retorts, when using the optimum thickness of coal layer, —3"—, is reduced to a point where the number of retorts required in a 35 self-contained gas generator set is excessive and imposes objectionable structural limitations.

Among the important features of the present invention is the flexibility of control which it permits of the B. t. u. value of the gases formed by the 40 gasification of fuel. In addition to the coal gas produced by the fuel distillation the gases produced in the generator in each cycle of the process may be collected separately or the said gases or any desired portions thereof may be mixed to give 45 a gas of the desired B. t. u. value. Moreover the heating value of these gases can be increased as desired by carburetting selected portions of the gases passing from the generator as previously described. Predetermined portions of the gases 50 are preferably burned in the upper portion of the generator and in the regenerator, and the resultant products of combustion, or part thereof, may be mixed with the unburned portions of the gases and carried to storage.

By the use of my invention as hereinbefore described I am able to effect the various objects thereof and to provide for the efficient concurrent carbonization and gasification of bituminous fuel and the like in a semi-continuous succession of 60 operations, at the same time recovering a high B. t. u. coal gas and a second combustible gas mixture of determinate B. t. u. value, together with primary tar, ammoniacal liquor, and the like. The invention is susceptible of modification within the scope of the appended claims.

I claim:

1. The process of producing a combustible gas and concurrently carbonizing fuel in relatively thin stationary layers which comprises passing a fluid through an incandescent fuel bed and concurrently passing the resultant highly-heated gases in indirect heat exchange relation with a column of fuel arranged in a thin annular layer adjacent to and out of direct contact with the said fuel bed, the said hot gases serving to supply at

least a portion of the heat for carbonizing the said fuel.

2. The process of concurrently producing combustible gas and carbonizing fuel in thin layers which comprises passing air through an incandescent fuel bed, passing the resultant highly-heated blast gases along and in indirect heat exchange relationship with a column of fuel arranged in a thin layer above the said fuel bed, thereafter passing steam through the said fuel bed and then passing the resultant water gas thus formed longitudinally of and in indirect heat exchange relation with the said column of fuel in the same direction with respect thereto as that of the said blast gases, thereafter superheating steam and passing the superheated steam along the fuel column in indirect heat exchange relation therewith, the direction of flow of the said superheated steam along the fuel column being in a direction opposite to that of the previous flow of the blast gases and the water gas, and recovering the various combustible gases produced.

3. The process of distilling and gasifying solid fuel which, when carried out in a water gas generator having one or more annular retorts suspended within the upper portion thereof, comprises the steps of heating a column of the fuel to be carbonized while disposed in a thin layer within a retort, by means of hot gases moving in indirect heat exchange relation with the said column around and on all sides of the retort, and supplying controlled amounts of secondary air at predetermined points lengthwise of the said retort and adjacent the fuel column therein in such manner as to control the temperature gradient in the column of fuel irrespective of the relative distance of each portion of the column from the source of the hot gases.

4. The process for distilling and gasifying solid fuel which, when carried out in a water gas generator having one or more annular retorts suspended within the upper portion thereof, comprises the steps of heating to a carbonization temperature a vertically-disposed column of fuel arranged in a thin confined layer within the retort 115 by means of hot gases flowing in indirect heat exchange relation with the former, the said column being heated indirectly from points on opposite sides of the thin layer to produce a higher temperature at the lower portion of the fuel column than at the upper portion thereof, and subsequently flowing hot gases along the said column downwardly from a point adjacent the upper end thereof to equalize the temperature existing at the two ends of the column and provide for a 120 uniform carbonization of the fuel.

5. In the semi-continuous process for distilling solid fuel in a column of thin annular cross-section and for gasifying the carbonized product by means of heat recovered from a combustible gas-making cycle, applied indirectly through inner and outer walls enclosing a carbonizing zone, the step of controlling the distribution of heat to the respective surfaces of the annular layer to control the relative proportion of the carbonization 135 effected at the respective inner and outer surfaces of the annular column.

6. In the semi-continuous process for distilling and gasifying solid fuel, the step of applying carbonizing heat to the solid fuel in an enclosed 145 column of thin annular cross section by hot gases moving upwardly along on both the inside and outside of the annular column out of contact with the fuel, and controlling the thickness of the fuel layer to provide a greater thickness thereof 150

adjacent the end of the column nearest the point of first contact of the hot gases therewith than at the opposite end of the column, to compensate for the effect of the higher temperature of the said gases at their point of first contact with the column, thereby facilitating a uniform time of carbonization of the fuel throughout the length of the column.

7. The semi-continuous process for concurrently carbonizing finely divided fuel in an elongated column of relatively thin annular cross section and for gasifying the carbonized product which comprises blasting air through an incandescent fuel bed to form highly heated blast gasses, passing said gases in indirect heat exchange relation with a column of fuel of annular cross section above but out of contact with said fuel bed while dividing the volume of the said highly heated gases so as to pass predetermined proportions thereof respectively adjacent the inner and outer surfaces of the annular column, and subsequently discharging the carbonized fuel onto the said fuel bed.

8. The process as defined in claim 7 including the step of burning predetermined portions of the said blast gases at selected points adjacent to the outer surface of the annular fuel column to indirectly heat the portions of the fuel remote from the said incandescent fuel bed to substantially the same temperature as that portion of the fuel column nearest to the said bed.

9. The semi-continuous process for concurrently carbonizing and gasifying fuel which comprises blasting air through an incandescent fuel bed and passing the resultant highly heated blast gases in indirect heat exchange relationship with at least one column of fuel of relatively thin annular cross section, thereafter passing steam through the said fuel bed and passing the resultant highly heated water gas in indirect heat exchange relation with the fuel being carbonized, the lower part of the fuel column being subjected to a higher temperature than the upper part of the said column in each of the said heat exchange steps, and thereafter passing superheated steam in indirect heat exchange relation with the column of fuel being carbonized in the direction opposite to the flow of the said heating gases along the said column for effecting a uniform carbonization throughout the length of the fuel column, and discharging the carbonized fuel onto the incandescent fuel bed for use in a subsequent gasification step and for supplying heat for carbonizing subsequent charges of fuel.

10. The semi-continuous process for concurrently carbonizing finely divided fuel in an elongated column of relatively thin annular cross section and for gasifying the carbonized product which comprises blasting air through an incandescent fuel bed to form highly heated blast gases, passing the said gases in indirect heat exchange relation with the inner and outer surfaces of a column of fuel of annular cross section above but out of contact with said fuel bed while dividing the volume of the said highly heated gases so as to pass predetermined proportions thereof respectively along the inner and outer surfaces of the annular column, and adjusting the rate of flow of heat to the said inner surface of the fuel column throughout the carbonization by heat storage and heat transmitting bodies.

11. The process of concurrently producing a combustible gas and of carbonizing solid fuel which comprises successively passing air and steam through an incandescent fuel bed while

dividing and passing portions of the resultant highly-heated combustible gases along and in indirect heat exchange relationship respectively with each of the lateral surfaces of a column of fuel arranged in a thin annular layer above the said fuel bed, thereafter passing superheated steam along and in indirect heat exchange relationship with the said column of fuel in a direction opposite to the direction of flow of the aforesaid highly heated combustible gases, then passing the said superheated steam through the fuel bed to produce a combustible gas, radiating heat to the said fuel column from the incandescent fuel bed during each of the above steps, recovering the various combustible gases produced, and discharging the carbonized fuel onto the said fuel bed.

12. The process as defined in claim 11 in which the effective heat transferred to the fuel column by the said combustible gases and superheated steam is in the range of from 1050° F. to 1500° F.

13. The process as defined in claim 11 in which the said column of fuel being carbonized is in a thin annular layer having a mean thickness of from 1½ inches to 5 inches.

14. The process of distilling and gasifying solid fuel disposed in a thin stationary layer, which comprises passing a combustion-supporting fluid through an incandescent fuel bed, and concurrently passing regulated portions of the resultant highly-heated combustible gases in indirect heat exchange relation respectively along both the outer and inner surfaces of a column of fuel arranged in a thin annular layer adjacent to but out of contact with the said fuel bed, the said hot gases serving to supply at least a portion of the heat for uniformly carbonizing the said fuel.

15. The process of concurrently producing a combustible gas and of carbonizing solid fuel, which comprises passing air through an incandescent fuel bed, dividing and passing regulated portions of the resultant highly-heated combustible gas along and in indirect heat exchange relation with the respective inner and outer surfaces of a column of fuel disposed in a thin annular layer above the said fuel bed, burning a selected portion of the said combustible gas during such passage and utilizing heat produced thereby for carbonizing the said fuel, carbureting another portion of the said combustible gas, utilizing potential and sensible heat of the first-named portion of the combustible gas for supporting the carburetion of the last-named portion of the said gas, and recovering the carbureted combustible gas.

16. The process of concurrently producing a combustible gas and of carbonizing solid fuel, which comprises passing air through an incandescent fuel bed, dividing and passing regulated portions of the resultant highly-heated combustible gas along and in indirect heat-exchange relation with the respective surfaces of a column of fuel disposed in a thin annular layer above the said fuel bed, burning a selected portion of the said combustible gas during such passage and utilizing heat produced thereby for carbonizing the said fuel, carbureting another portion of the said combustible gas, utilizing potential and sensible heat of the first-named portion of the combustible gas for supporting the carburetion of the last-named portion of the said gas, recovering the carbureted combustible gas, thereafter passing superheated steam along and in indirect heat-exchange relation with the said fuel column in a direction opposite to the direction of flow

- of the first-named combustible gas, then passing the said superheated steam through the fuel bed to produce a second combustible gas, recovering the latter, and radiating carbonizing heat to 5 the said fuel column from the incandescent fuel bed during the respective steps of passing air and steam in the said heat-exchange relation with the fuel column. 17. The process of concurrently producing a 10 combustible gas and of carbonizing solid fuel, which comprises passing air through an incandescent fuel bed, dividing and passing regulated portions of the resultant highly-heated combustible gas along and in indirect heat-exchange relation 15 respectively with each of the surfaces of a column of fuel disposed in a thin annular layer above the said fuel bed, thereafter passing steam through the fuel bed, thereby producing a second combustible gas, dividing the last-named combustible gas and passing regulated portions thereof along and in indirect heat-exchange relation 20 with the respective surfaces of the annular fuel column, then carbureting a selected portion of the last-named combustible gas and supporting the said carburetion by heat regenerated in the 25 process, passing superheated steam in indirect heat-exchange relation with the said fuel column in a direction opposite to the flow of the last-named combustible gas, and then passing the 30 superheated steam through the fuel bed to produce a third combustible gas, and recovering the various combustible gases produced during the respective steam treatments. 18. The process of concurrently producing a 35 combustible gas and of carbonizing solid fuel, which comprises successively passing air and steam through an incandescent fuel bed while dividing and passing regulated portions of the resultant highly-heated combustible gases up- 40
- wardly along and in indirect heat-exchange relation respectively with each of the lateral surfaces of a column of fuel disposed in a thin annular layer above the said fuel bed, burning the first portion of the combustible gases produced during the said air passage at selected points longitudinally of the said column for carbonizing the fuel in the said column, regenerating additional sensible and potential heat of the combustible gases from the air treatment and utilizing the thus regenerated heat for supporting the subsequent carburetion of the combustible gases produced in the process, thereafter passing superheated steam downwardly along and in indirect heat-exchange relation with the said column of fuel and thence through the fuel bed to produce a combustible gas, carbureting the respective combustible gases produced during the steam treatments, recovering the same, and periodically discharging the carbonized fuel upon the said fuel bed. 19. The semi-continuous process for distilling and gasifying solid fuel in which the latter during distillation thereof is disposed in a column of thin annular cross-section, which comprises 100 heating a column of the solid fuel to be carbonized, while disposed in a thin annular layer, by means of hot gases moving longitudinally of and in indirect heat exchange relation with the said column through each surface of the said 105 layer, and burning controlled amounts of the said hot gases at selected points spaced lengthwise of and adjacent the fuel column in such manner as to control the temperature of the fuel at such points in the column irrespective of the 110 relative distance of these points from the source of the said hot gases.
